UNITED STATES PATENT OFFICE

RONALD BUCK, OF MANCHESTER, ENGLAND

DIVING RAFT

Application filed August 26, 1931, Serial No. 559,355, and in Great Britain April 1, 1931.

The object of my invention is to provide for swimming baths and other bathing places, a diving raft which is capable of providing a means of safe amusement and adding fresh enjoyment to the activities of divers, non-divers and non-swimmers.

According to my invention I provide a diving raft having a rising upper part and footholds adapted to assist bathers in climbing to the top thereof, means being provided on the raft to restrict tilting or rotary movement about a horizontal axis and thereby assist the bathers in climbing.

The footholds may be arranged in a localized manner or to surround the rising upper part.

Float means, weighting means, anchoring means or shaping of the lower part of the raft may be employed to limit, hinder or prevent tilting of the raft.

Handhold means may be provided at the upper part of the raft to assist bathers in the latter part of the climb.

The footholds preferably comprise ledges or projections of relatively soft material and may also be adapted to serve also as handhold means.

The float means preferably are of a relatively soft nature.

The weighing means are preferably arranged in such a manner that they do not produce loose or abruptly projecting parts.

The raft may be inflated or contain air at atmospheric pressure, or be stuffed with buoyant material.

In the accompanying three sheets of drawings—

Figure 1 is a front view, partly in section of a diving raft.

Figure 2 is a plan view thereof.

Figure 3 is a fragmentary view in vertical section and

Figure 4 is a fragmentary front view drawn to a larger scale and illustrating more clearly a detail.

Figure 5 is a front elevation showing a second construction.

Figure 6 is a front elevation illustrating a third construction.

Figure 7 is a fragmentary front view, part-

ly in section and illustrates a modification.

Figure 8 is a fragmentary front view, partly in section and illustrates another modification.

Figure 9 is a fragmentary front view, partly in section and illustrates a further modification.

Figure 10 is a fragmentary front view, partly in section and illustrates a further modification.

Figure 11 is a fragmentary plan view in section taken on a line corresponding with line 11—11 of Figure 10.

Referring to the drawings, in the construction shown in Figures 1 to 4, I provide a casing 1 of a suitable fabric or material, preferably a fibrous fabric which may be rendered waterproof by any suitable means.

The casing has substantially the shown shape with a dome-like upper part and contains an inflatable bladder 2, Figure 3, for example of india-rubber. The whole, when inflated as shown, is adapted to float. The casing 1 may be of any other suitable shape, for example that of an animal, fish, bird, giant, allegorical figure, and so forth and may contain more than one inflatable bladder.

The casing 1 has secured to its exterior pieces 3 of fabric, see more particularly Figures 3 and 4, for example by stitches 4 and/or any other suitable means. Each piece of fabric extends round a padding 5 of comparatively soft material, for example rope and is secured round the padding 5 by stitches 6 and/or any other suitable means. If desired, the piece 3 may be drawn together at the ends, for example by stitches 7 and/or other suitable means to cover the ends of the padding 5.

The pieces 3 are arranged to form one or more series of footholds arranged at suitable distances one above the other. The projections produced by the padding 5 are sufficient to assist the bather in climbing up the casing, but owing to their comparatively soft nature, can not injure the bare feet or other parts of the bather and can not trap the bather. Furthermore, the footholds which the projections give are not such as to enable the bather to climb without some care, ex-

erion and skill and consequently mounting of the ball is rendered more interesting and exciting.

5 A ring 8 of comparatively soft material, for example rope, may be provided at the top of the casing to serve as a handhold for those who climb and those who have reached the top.

10 Depending, loose members 9, for example hand ropes attached at the upper end only, may also be provided to assist the bathers in completing the climb.

15 An inflated tube 10 for example of rubber or the like, and formed continuous or with closed ends, surrounds the casing at the lower part thereof. The tube 10 is maintained in its surrounding position by a fabric or other suitably soft covering 11 secured to the casing and preferably permitting the tube 10 to rise a suitable distance up the casing when placed in the water. The tube floats entirely or partly unsubmerged. Its purpose is to lend sufficient stability to the whole against tilting or turning on a horizontal axis, to 20 partially counteract the effect which the weight of a bather would otherwise have thereon when he attempted to climb up the casing. Preferably the stabilizing action is maintained sufficiently low as to permit a predetermined amount of tilt or rock under the weight of a bather or bathers and thereby render the climb more amusing and exciting.

25 The lowermost part of the casing may be somewhat flattened, for example as shown, 30 to assist in obtaining stability and enabling the diving raft to float in more shallow water.

35 Preferably the diameter of the casing is large for example from 5 to 12 feet upwards in order to give a good height for diving and 40 make the climbing thereof an achievement.

45 Instead of providing an inflatable tube 10 in the covering 11, the covering may be filled with buoyant material such as capoc, ground cork, and so forth, or it may be adapted to 50 fill itself with the water from that in which the diving raft floats. One method of adapting it to fill itself with water is to provide perforations in its upper part and/or holes in its lower part controlled by non-return 55 valves, for example in the form of flaps or the like arranged inside the cover over the last named holes, and to provide the covering 11 with means whereby it maintains itself in an extended or distended state to enable the 60 water to enter and fill it. One suitable means comprises cross partitions of flexible or comparatively stiff material arranged at suitable distances apart. Another suitable means consists of spaced plugs of padding which 65 preferably is of an absorbent nature. The padding may be maintained in position by attachment thereof to the covering or by disposing it in pockets formed by the aid of suitable cross partitions in the cover. In the 70 example illustrated in Figures 10 and 11, the

casing has bags or buckets 28 attached in an annular row to its lower part, and connected together externally by a thick rope ring 29 attached to all of the bags or buckets 28. Holes 30 are provided in the bags or buckets 28 to allow water to enter them and act as ballast and thereby impart the desired stability to the raft. The bags or buckets 28 are preferably of stout canvas so as to have flexibility.

75 The water contained in the covering 11 or bags or buckets 28 constitutes a weight, which, when the raft is tilted acts at the raised side of the raft to return the raft to its initial position or prevent further tilting 80 under the weight of the bather.

85 The covering 11, or bags or buckets 28 and the water therein, and also the padding, where employed, are of a relatively soft nature and therefore are not liable to injure the bathers. If required the cross partitions may be arranged in oblique slanting positions. The covering 11 or the bags or buckets 28 may be completely filled with absorbent material, for example sponge rubber. Instead 90 of relying on water as ballast, the covering 11 or bags or buckets 28 may be filled with sand.

95 It will be observed that in the construction shown in Figures 1 to 4, there are four series of projections, which series are spaced irregular distances apart, but it is to be understood that there may be any desired number and arrangement of series of projections. In the example shown in Figure 10 the lower 100 part of the casing is provided with two annular projections 31 and 32 which also serve as foot and hand holds. The rope ring 29 also serves as a foot and hand hold.

105 In the construction shown in Figure 5, there are four series of projections spaced equal distances apart and a predetermined amount of stability is obtained by forming the inflated casing 12 with the shown shape of bottom.

110 In the construction shown in Figure 6 there is only one series of projections which extend completely round the inflated casing 13 and the top of the casing 13 is slightly flattened to facilitate standing thereon, 115 whilst a predetermined amount of stability is obtained by shaping the bottom of the casing as shown.

120 Figure 7 illustrates another method of obtaining a predetermined amount of stability. A series of closed pockets 14, 15, 16 of progressively smaller size are provided, the pocket 14 being secured to the inflated casing 17, the pocket 15 to the pocket 14 and the pocket 16 to the pocket 17. The pockets are of comparatively soft material and are filled with suitable ballast 18, for example sand or other comparatively soft or yielding material. The pockets may be lined with sand-proof material and be rendered waterproof. 125 130

In the method illustrated in Figure 8 a predetermined amount of stability is obtained by means of bags 19 filled with suitable ballast of comparatively soft or yielding material, secured to the casing 20 and enclosed in a pocket 21 of comparatively soft material, the pocket 21 being also secured to the casing 20.

In all of the above stabilizing means there is nothing to hurt or injure the bather's feet or other parts of his body by coming into contact therewith and in the unlikely event of the raft being turned completely over due to the combined efforts of many bathers, the stabilizing means in subsequently descending towards the water cannot strike a bather in such a manner as to injure him.

In arrangement shown in Figure 9, stability is obtained by means of ropes or tubes composed of a ring 22 having four depending parts 23 which converge to a point and having a weight 24 which is retained in position by the parts 23. The ring 22 is secured to the lower part of the inflated casing 25.

Instead of or in addition to providing a weight 24, the frame may be attached by means of a slack chain 26 to the ground or to a flat, heavy weight 27 which rests on the ground, the weight 27 being sufficiently heavy as to be unliftable by the bathers. An inverted hollow pyramid of fabric, of the same shape as the said frame may be substituted for the frame. In lieu of providing the casing of the raft with an inflated bladder or bladders, it may be retained in its distended state by a hollow frame or foundation of wickerwork, basketwork and so forth, or may be stuffed with buoyant material. I however prefer to employ an inflatable bladder or bladders because the raft is thereby rendered readily portable.

I claim—

1. A diving raft comprising a casing having a rising part, an inflated bladder in the said casing, footholds of soft material distributed over the rising part of the casing, hand ropes depending from the casing, water buckets depending from the lower part of the casing and apertures in the buckets for automatically filling them from the water in which the raft floats.

2. A driving raft according to claim 1, wherein the footholds comprise horizontal ledges consisting of horizontally disposed cores of textile material, and tight coverings attached horizontally to the casing and completely enclosing the cores.

In testimony whereof, I have signed my name to this specification at Manchester in the county of Lancaster, England, this 14th day of August, 1931.

RONALD BUCK.
